CLAIM

The ornamental design for a vehicle programming and diagnostic interface, as shown and described.

DESCRIPTION

FIG. 1 is a front perspective view of a vehicle programming and diagnostic interface according to my invention;

FIG. 2 is a front view of a vehicle programming and diagnostic interface according to my invention;

FIG. 3 is a top view of a vehicle programming and diagnostic interface according to my invention;

FIG. 4 is a side view of a vehicle programming and diagnostic interface according to my invention the undisclosed side view is a mirror image thereof;

FIG. 5 is a back view of a vehicle programming and diagnostic interface according to my invention; and,

FIG. 6 is a bottom view of a vehicle programming and diagnostic interface according to my invention.

The broken lines are shown in the views for illustrative purposes only and form no part of the claimed design.
